UNITED STATES PATENT OFFICE.

WILLIAM R. CLAXTON, OF BARTOW, FLORIDA.

LEGGING.

Specification of Letters Patent. Patented Jan. 9, 1917.

1,211,411.

Application filed April 24, 1915. Serial No. 23,681.

To all whom it may concern:

Be it known that I, WILLIAM R. CLAXTON, a citizen of the United States, residing at Bartow, in the county of Polk and State of Florida, have invented new and useful Improvements in Leggings, of which the following is a specification.

This invention relates to improvements in leggings, the object of the invention being 10 to provide an improved legging which is made of sheet metal so as to be impervious to water and hence serves to protect the trousers of the wearer from becoming soaked when walking in wet grass or swampy 15 places; which is proof against the bites of rattle snakes and the like; which can be readily put on and taken off and which can be very readily secured.

The invention consists in the construction, 20 and arrangement of devices hereinafter described and claimed.

In the accompanying drawing Figure 1 is a perspective view of a legging constructed in accordance with my invention. Fig. 2 is 25 a detail vertical sectional view of the same. Fig. 3 is a detail transverse sectional view of the same. Fig. 4 is a plan of the legging when in straightened out or flattened condition.

30 In accordance with my invention the legging 1 is made from a plate of suitable sheet metal, preferably aluminum, which is extremely light and yet strong and durable and not liable to corrode. The plate is incurved 35 at its center at the upper and lower edges as 2-3, and is rounded at the side edges as at 4-5 and is also rounded at the corners as at 6-7, the edges of the plate being doubled inwardly to form a reinforce 8 and 40 provide a finish at the edge.

The plate is rolled to form a tubular body of oval form cross sectionally, to conform to the shape of the leg, which enables the legging to be readily fitted to the leg with the 45 rounded end edges 4-5 overlapping and coacting with the rounded corners in providing the legging with a substantially V-shaped opening above said overlapping portions, said overlapping portions lying 50 enabling the legging to be contracted and expanded diametrically as required.

The plate is provided upon one side, at points near the overlapping edges with U-shaped loops 9 each of which is made of a

single wire, said loops being arranged on 55 the outer side of the legging at spaced points so that the said arms are partly within and partly without the legging the arms of the loops being clenched as at 10 and being also soldered or otherwise suitably secured as at 11. A cord 12 for tying the legging is also provided, which passes through and connects the loops and by means of which the legging may be secured when adjusted.

To prevent the lower edge of the leggings 65 from wearing the shoe I provide a bearing tab 14 which is made of leather or other suitable flexible material, and is secured by means of rivets or the like at a point near the lower edge of the plate, the width of the 70 bearing tab being such that the lower edge of said tab projects below that of the metallic body of the legging and in advance of the lowermost V-shaped opening to bear directly on the portion of the shoe overlying 75 the arch of the foot and to keep the metal body of the legging from contacting with the shoe top.

I would have it understood that any suitable kind of sheet metal may be used in the 80 manufacture of my improved legging within the scope of my invention as defined by the appended claims and that modifications in the form, proportion and construction of the parts may also be made.

Having thus described my invention I 85 claim:-

1. A legging comprising a flexible metal plate having rounded corners and rolled to form a body having overlapping end portions, said end portions having outwardly curved marginal edges co-acting with said rounded corners in providing the body with substantially V-shaped openings above and below said overlapping end portions, and a 90 bearing strip for contact with a shoe extending beyond the lower edge of said body and in advance of the lowermost of said openings.

2. A legging comprising a plate of resilient material having rounded corners and rolled to form a body having overlapping end portions, said end portions having outwardly curved marginal edges coacting with said rounded corners in providing the body 100 with substantially V-shaped openings above and below said overlapping end portions, a strip of flexible material extending circum-

ferentially about the lower edge of said body and projecting beyond the same in advance of the lowermost of said openings, and a pair of lacing loops on said body having closed ends spaced therefrom and arranged adjacent said overlapping end portions.

Copies of this patent may be obtained for five cents each, by addressing the "Commissioner of Patents, Washington, D. C."

In testimony whereof I affix my signature in presence of two witnesses.

WILLIAM R. CLAXTON.
